CLOTHES HOOK AND UTILITY HANGER

Richard J. Lukeman, Montreal, Quebec, Canada

Application October 13, 1944, Serial No. 558,572
In Canada October 19, 1943

1 Claim. (Cl. 70—59)

This invention relates to article hangers and has, for its object, the provision of an improved form of article hanger adapted to be locked in an article-retaining condition so that coats, hats or other articles suspended therefrom cannot be removed until after the locking mechanism has been released by a person equipped with a proper key.

The article hanger provided in accordance with this invention comprises a base plate adapted to be secured in a vertically extending position against a wall or other supporting structure, an arm extending outwardly and upwardly from said base plate and constituting an article-supporting hook or peg adapted to be received through an opening provided in an article such as a hat or coat which is to be suspended therefrom and a locking bar having one end pivoted to said plate and the other end formed to fit over the upper end of said arm, the last mentioned end of the locking bar constituting a lock casing containing a key-operated locking mechanism for locking it to the said upper end of the arm. In this arrangement the locking bar spans the space between the plate and the upper end of the article-supporting arm and prevents an article suspended from said arm being removed by slipping it over the upper end of the arm.

Another feature of the invention consists in providing, in association with said improved article hanger, electrical signalling means for sounding an alarm in the event that an attempt is made to circumvent the locking mechanism by sawing or cutting through a portion of the article supporting arm or the associated locking bar when the hanger is in its locked article-supporting condition.

Proceeding now to a more detailed description reference will be had to the accompanying drawing, in which the single figure is a view partly in side elevation and partly in vertical section of an article hanger installation embodying my invention.

Referring more particularly to the drawing, 5 designates a base plate adapted to be secured in a vertically extending position against a wall or other supporting structure. This plate carries an article-supporting arm 6 which extends outwardly and upwardly from the side of the plate opposite that secured against the wall or other supporting structure. The arm 6 is here shown as a curved hollow tube provided with a closed end 7 having a portion thereof shaped to provide a flange-forming element 8. The arm 6 is reinforced against bending by an internal rein-

forcing core 9 which preferably consists of a rod or bar of solid metal. A conductor 10 is interposed between the core 9 and the inner wall of the tubular arm 6 and terminates, at its inner end, adjacent the closed end 7 of the arm. Conductor 10 is insulated from both the arm 6 and the reinforcing core 9 and is connected to one terminal of a battery 11 or other source of electrical energy, the remaining terminal of which is connected, through an electric bell 12 or other electrically actuated signalling means, to a terminal 13 attached to the arm 6. A locking bar supporting fitting 14, carried by an upper portion of the plate 5, is secured to one end of a locking bar 15 by means of a ball and socket joint 16. The opposite end of locking bar 15 is constituted by a casing 17 provided with an opening 18 which permits it to be fitted over the upper end of the arm 6 so that the flange-forming portion 8 of said arm extends into said casing and is adapted to be releasably secured therein by locking means 19 forming part of a key-operated locking mechanism contained in said casing and adapted to be operated and released by means of a suitable 25 removable key 20.

When the hanger described herein is to be used as an article-locking hanger the article suspended therefrom must be provided with an opening through which the upper end of the article-supporting arm 6 may be passed. For example, I have shown in the present drawing an element 22 which may be taken as representing a portion of the brim of a hat which is suspended from the arm 6. In order to permit the hat to be so suspended the brim portion 22 is provided with an opening 23, preferably reinforced by a grommet 24. This opening 23 permits the brim of the hat to be slipped over the arm 6 and then locked against removal by locking the flange-forming element 8 of said arm in place within the lock casing 17 of the locking bar 15. If an attempt is made to circumvent the locking mechanism by sawing or cutting through the arm 6 at a point between the plate 5 and the lock casing 17, the sawing or cutting tool used for this purpose will cut through the insulation of the conductor 10 and will thus contact the metal of said conductor and thereby complete a circuit for the flow of current through the alarm bell 12 which is thus actuated to sound an alarm. The locking bar 15 is also provided with a strengthening core 25 and an insulated conductor 26 which correspond, respectively, to the previously mentioned core 9 and conductor 10. The conductor 26 extends from 55 the casing 17 to and through the remote end of

the ball and socket fitting 14 and is connected to the same terminal of battery 11 to which conductor 10 is connected. An additional conductor 28 connects the fitting 14, through bell 12, to the same terminal of battery 11 to which the arm 6 is connected. It will thus be seen that any attempt to circumvent the locking mechanism by cutting through the locking bar 15 or the ball and socket joint 16 would also complete circuit connections for actuating the bell 12.

Having thus described what I now conceive to be the preferred embodiment of this invention it will be understood that various modifications may be resorted to within the scope and spirit of the invention as defined by the appended claim.

I claim:

An article hanger comprising a base plate adapted to be secured in a vertically extending position against a wall or other supporting structure, an article-supporting arm extend- 20

ing outwardly and upwardly from the lower portion of said plate, the upper end of said arm being adapted to be passed through an opening provided in a part of the article to be supported by said arm, a vertically swingable theft-preventing member having one end pivoted to the upper portion of said plate and provided, at its opposite end, with a lock casing having an opening through which the upper end of said article-supporting 10 arm projects into said casing when said theft-preventing member is arranged in a horizontal position bridging the gap between the plate and the upper end of said arm, and key-operated locking means in said casing adapted to be operated 15 into locking engagement with the upper end of said arm to secure said theft-preventing member in its horizontal position bridging the gap between the upper end of the arm and said plate.

RICHARD J. LUKEMAN.
